UNITED STATES PATENT OFFICE.

JAMES B. PATTERSON, OF PHILADELPHIA, PENNSYLVANIA.

DESIGN FOR A HAMMOCK-STRETCHER.

SPECIFICATION forming part of Design No. 20,102, dated August 12, 1890.

Application filed July 15, 1890. Serial No. 358,837. Term of patent 3½ years.

To all whom it may concern:

Be it known that I, JAMES B. PATTERSON, a citizen of the United States, residing at Philadelphia, in the county of Philadelphia and State of Pennsylvania, have invented and produced a new and original Design for a Suspending-Hammock Stretcher, of which the following is a specification, reference being had to the accompanying drawing, forming part thereof.

The leading feature of my design consists in a triangle-shaped loop, having curved sides

A A, center braces B B, and dividing-lugs C C, as shown in the drawing.

What I claim as my invention, and desire to secure by Letters Patent, is—

The design for a suspending-hammock stretcher, as shown in the accompanying drawing.

J. B. PATTERSON.
